UNITED STATES PATENT OFFICE.

MAXMILIAN ERNST, OF CLEVELAND, OHIO.

DESIGN FOR A BOX-COVER.

SPECIFICATION forming part of Design No. 25,004, dated December 24, 1895.

Application filed May 9, 1895. Serial No. 548,776. Term of patent 7 years.

To all whom it may concern:

Be it known that I, MAXMILIAN ERNST, a citizen of the United States, residing at Cleveland, in the county of Cuyahoga and State of Ohio, have invented and produced a new and original Design for Box-Covers, of which the following is a specification, reference being had to the accompanying drawings, forming a part thereof.

10 Figure 1 is a picture of a box-cover made according to my design. Fig. 2 is a central vertical section of the cover applied to the box *a*.

15 The box-cover *b* is circular or approximately circular in plan, and the upper side or top thereof, that is convex, is suitably in-

dented to form a cluster of rounded projections representing a bunch of grapes, and is provided with other rounded and larger projections to represent the outlines of larger 20 fruit—such, for instance, as a peach, pear, or plum.

What I claim is—

The design for a box-cover herein shown and described.

In testimony whereof I sign this specification, in the presence of two witnesses, this 6th day of May, 1895.

MAXMILIAN ERNST.
